SCRAPER

Robert B. Bennett, Detroit, Mich.

Application January 1, 1944, Serial No. 516,690

4 Claims. (Cl. 15—236)

1

This invention relates to scrapers and more particularly to the type including a coiled replaceable insert scraper member adapted to chiseling engagement with the object scraped, as for instance a utensil.

Although there are on the market numerous aids, such as metal, metal wool, rubber and plastic scrapers, for scraping surfaces such as dishes, pans, painted and other surfaces, they all have one or more major faults which, to offset long soaking of especially the cooking utensils, cause the housewife to resort to using her fingernails to remove the most stubborn particles. Broken fingernails, injured hands and sore fingers often result from this practice which is effective only to a limited degree. The scrapers heretofore available, especially metal wool, often puncture the skin.

To overcome this difficulty a novel scraper is disclosed herein which will effectively and easily remove obstinate food particles or other matter closely adhering to the surface of dishes or kitchen utensils being washed.

It is the object of the present invention to provide a suitable holder and applicator within which is operatively provisioned and stored in coiled form a continuous strip of flexible relatively stiff material as for instance a plastic or metallic substance.

It is the object of the present invention to provide a scraper feeding throat member forming a part of the coiled scraper holder and projecting therefrom, as a means of manually applying the scraper insert to the surface of dishes or other kitchen utensils.

It is the object of this invention to make a portion of said throat member flexible, permitting manual frictional pressure for resisting relative movement of the scraper insert back into the throat member during the scraping operation. It is contemplated that various other means may also be employed for providing such frictional relationship.

It is the further object herein to provide a feeding mouth at the outer end of said throat, of various regular or irregular cross sectional areas for effecting a degree of stiffness to the flexible projecting scraper member, at the same time permitting said scraper to assume various shapes coinciding to the surface or curvature of the object or utensil sought to be scraped, as well as being adapted to frictionally resist receding movement thereof.

It is the object herein to make said mouth portion sufficiently flexible to allow manipulation thereof resulting in a change in shape of the pro-

2

jecting scraper to fit the shape of the utensil. On the other hand it may be desired to make said mouth portion stiff enough to assume a predetermined shape for all utensil surfaces, and not requiring manipulation.

It is the still further object herein to provide a coil of scraping material within the scraper holder together with means secured to said coil for limiting feeding movement of the portion thereof projecting out from the mouth of the scraper.

Such means secured upon the inner end of the coiled scraper substance, as for instance a bar or cross member, will also facilitate the manufacture of the scraper device in facilitating insertion of the coil within the holder. On the other hand manually operable transversely movable means may be provisioned within the throat member for operative frictional engagement direction with the scraping material.

20 These and other objects will appear in the following specification and claims. The invention therefore relates to the various arrangements of the elements thereof and their combination as illustrated in the drawing in which—

25 Fig. 1 is a side elevational view of the scraper.
Fig. 2 is a right end elevational view thereof.
Fig. 3 is an end elevational view of a different scraper mouth opening.

30 Fig. 4 is an end elevational view of a slightly different form.

Fig. 5 is an end elevational view of a still different form.

Fig. 6 is a similar view of another form of mouth opening.

35 Fig. 7 is a fragmentary perspective view of the scraper material.

Fig. 8 is a fragmentary view of a scraper edge.
Fig. 9 is a slightly different form thereof.

Fig. 10 is a still different form thereof.

40 Fig. 11 is a fragmentary view of another form of scraper edge.

Fig. 12 is an elevational section of the scraper.
Fig. 13 is a fragmentary elevational view of a handle therefor.

45 Fig. 14 is a fragmentary elevational view of a different form of scraper neck or throat member.

Fig. 15 is a fragmentary elevation of a different form of scraper.

50 Fig. 16 is a fragmentary elevation showing a scraper brake.

Fig. 17 is a fragmentary sectioned view of the same.

It is understood that the above figures illustrate merely preferable embodiments of the invention, and that other embodiments are contemplated.

within the scope of said invention as defined in the accompanying claims.

Referring to the drawing the scraper holder shown in Figs. 1 and 2 consists of hollow substantially circular shell housing 11 with elongated throat or neck member 12 forming a part thereof and projecting therefrom, which terminates at its outer end in the mouth 13.

The top and bottom portions of mouth 13 as shown in Fig. 2 is concaved at 14 providing a frictional pressure engagement upon the top and bottom surfaces of flexible plastic scraper member 15 which projects through said mouth. It is understood that said scraper members, preferably in coiled form, may be made of any other suitable relatively stiff and flexible material. A means is thus afforded for preventing scraper 15 from being pushed back into the throat member 12 when in operative engagement with the substance sought to be removed from the utensil during a washing operation. The constriction in mouth 13 also acts as a stiffener for the portion of scraper member 15 which projects out from the end of throat 12.

With mouth opening 14 arcuate in shape it is understood that the scraper strip 15 comes out therefrom as a cylindrically curved or arcuate sheet which then bends flat as in Figs. 2 and 7 when coming in contact with the surface to be scraped. It is this change in shape of the scraper which results in stiffening of the operative end of the scraper.

The top surface portion of the scraper holder between points 13 and 16 is sufficiently flexible so that finger pressure thereon will also effect a frictional relationship between holder 11—12 and the flexible scraper member 15 coiled therein at 17 and extending through throat 12 as shown in Fig. 12, to further prevent backward movement thereof when used in a scraping operation.

Fig. 1 shows the point of contact 18 of flexible scraper member 15, with respect to the dish or utensil surface, while the outer edge 19 is adapted for operative chiseling contact with the material sought to be removed from said surface. The curved under surface at 20 of throat 12 provides gripping means for manually operating the scraper, the recess formed thereby affording sufficient clearance to protect the knuckles of the user when utilizing said scraper.

Figs. 3, 4, 5 and 6 illustrate additional slightly different shapes of mouth 13 through which scraper 15 projects, whereby various degrees of stiffness and curvature of the operating edge 19 may be obtained depending upon the use to which the scraper is put.

Fig. 7 fragmentarily illustrates scraper member 15 and the stiffening effect obtained therein by curving the same at 21 corresponding to a curved mouth 13 for the scraper throat 12 as shown in Fig. 6. At the same time the portion 22 adapted for sliding engagement with the surface to be scraped is substantially flat with the sharp cornered chiseling edge 19.

Fig. 7 brings out the additional novel stiffening effect achieved by feeding the strip through a curved opening then pressing it to flatten it against the surface scraped. Great force can thereby be exerted, more than by merely curving the weak flexible strip.

Figs. 8, 9, 10 and 11 illustrate various shapes which can be made or cut in chiseling edge 19 which may be effected by cutting the end of scraper member 15 with a scissors or other suit-

able means, in order to carry out the particular scraping task contemplated.

Figs. 8 through 11 bring out two other novelties not found in present scrapers, i. e., the possibility of cutting the end to renew the sharp chisel edge, and the cutting of it in endless variety of shapes to fit any shape of utensil encountered.

Fig. 14 fragmentarily illustrates the throat portion 12 of scraper holder 11, with its inner and outer surfaces undulated or irregularly curved at 23 providing on the inside thereof a plurality of frictional engaging points for scraper member 15, whereby a relatively high degree of stiffness is attained in scraper 15, as well as means for aiding in retaining the scraper in operative position. It is contemplated that the upper surface of throat 12 may be thin at point 24, for instance, permitting manual pressure engagement of the inner surface of throat 12 against member 15.

Housing 11 as in Fig. 12 may have an opening 25 therein for hanging the scraper when not in use. Or on the other hand a secondary handle 26 may be formed extending from scraper housing 11 oppositely from throat 12 as shown fragmentarily in Fig. 13, having therein opening 27 for hanging the scraper. Oppositely arranged concaved portions 28 intermediate members 26 and 11 provide additional finger gripping means facilitating operation of the scraper.

Point 24 on throat 12 indicates a relatively thin portion which is readily flexible permitting manual frictional engagement thereof with the adjacent area of the scraper strip 15 for obtaining a braking action thereon.

The fragmentary illustration in Fig. 15 shows oppositely disposed openings 29 and 30 formed within housing 11. Access is thus provided to the hollow interior thereof for inserting a coil of scraper material 15, which, rotatably nested therein, may be manually projected outwardly through throat 12 for operative positioning through mouth 13 as shown in Fig. 1. No such openings are provided in the illustration of Fig. 1, so that the coiled sheet of scraping material 15 must be initially inserted uncoiled through mouth 13 and throat 12, to be nestingly coiled within housing 11. In this case the scraper material 15 is outwardly fed from the outer end of the throat. However as shown in Fig. 12 said material may be fed by the fingers through openings 29 and 30 within shell housing 11.

Fig. 15 shows a mandrel or handle 31 transversely projected through openings 29 and 30 in housing 11, secured on the end 32 of the coiled sheet of scraper material 15. Thus by manual rotary application of mandrel 31 within openings 29 and 30 strip 15 may be pushed or pulled through throat 12 for operative projection through mouth 13 of said holder. Such open structure of housing 11 not only facilitates loading of the scraper housing, but also permits free access to the interior thereof as an aid in cleaning.

Fig. 16 fragmentarily shows housing 11 and throat 12 illustrating the manually operable braking means 33, as shown in detail in Fig. 17 projecting through opening 34 in throat 12, with its inner flanged portion 35 adapted to frictionally engage the surface of scraper strip 15, and with its outer flanged portion 33 providing means for manually effecting braking action to prevent relative movement of said scraper when in use.

The coiled sheet of scraping material provisioned for progressive manual adjustment through the holder mouth thus provides means

for effecting a new scraping edge as the same wears from time to time, or otherwise becomes damaged. Many advantages are obvious from this construction and particularly as contrasted with various abrasive substances, such as steel wool, which are adapted to wear down the material or food particles sought to be removed from the utensil. On the other hand the scraper member shown herein actually chisels such substance from the surface of the utensil by a manually effective sliding action over the surface thereof.

It is understood that the form of scraper shown in the drawing is easily molded; and is assembled in any manner and of any material known to the molding trade to be convenient, efficient and inexpensive.

The present invention provides a scraper member the operative edge of which may be cut easily to fit the shape of the utensil surface scraped; and furthermore may by cutting from time to time be kept sharp.

As shown in Fig. 12, throat 12 is curved as it joins housing 11, providing an arcuate feeding slot. This curvature provides substantial frictional resistance to backward or receding movement of the scraper strip when operative.

Having described my invention reference should be had to the claims which follow for determining the scope thereof.

I claim:

1. A scraper for utensils comprising a hollow container, having oppositely disposed lateral openings therein, a hollow longitudinally projected throat member forming a part of said container, a coil of relatively stiff scraper material inserted through said lateral openings, nested within said container, with one end of said coil projecting through said throat member providing beyond the outer end thereof an operative scraper edge, and a manually operable cross member projected through said lateral openings and secured to the inner end of said scraper coil for effecting longitudinal adjustments of said scraper member within said throat member.

2. A scraper for utensils comprising a hollow

container, having oppositely disposed lateral openings therein, a hollow longitudinally projected throat member forming a part of said container, a coil of relatively stiff scraper material inserted through said lateral openings, nested within said container, with one end of said coil projecting through said throat member providing beyond the outer end thereof an operative scraper edge, a manually operable cross member projected through said lateral openings and secured to the inner end of said scraper coil for effecting longitudinal adjustments of said scraper member within said throat member, and a manually operable transversely movable member provisioned through the top surface of said throat member for effecting frictional engagement with said scraper member.

3. A scraper for utensils comprising a hollow container, an irregularly shaped slotted longitudinally projected throat member forming a part of said container said irregular shape consisting of a plurality of longitudinal arcuate undulations in the top and bottom of said throat member, and a coil of a relatively stiff scraper material provisioned within said container with one end of said coil projecting through said throat member providing beyond the end thereof an operative scraper edge, the undulations of said throat member providing a plurality of frictional contacts with said material.

4. A scraper for utensils comprising a hollow container, a hollow longitudinally projected throat member forming a part of said container, and having an arcuately shaped mouth on the outer end thereof, and a coil of a relatively stiff plastic material provisioned within said container with one end of said coil projecting through said throat and mouth members providing beyond said mouth an operative scraper edge, said mouth defining a corresponding arcuate shape in said material, the outer end of said material being adapted for flattening upon a surface to be scraped, whereby said arcuate portion terminating in said flattened portion will provide a greatly stiffened scraper edge.

ROBERT B. BENNETT.
